INDICATING SYSTEM FOR REFRIGERATORS

Filed Nov. 18, 1927

Patented Feb. 19, 1929.

1,703,068

UNITED STATES PATENT OFFICE.

FRANK J. SCHROEDER, OF ROCHESTER, NEW YORK.

INDICATING SYSTEM FOR REFRIGERATORS.

Application filed November 18, 1927. Serial No. 234,255.

The object of this invention is to provide a form of mechanism that will automatically indicate the amount of ice there is in the customer's refrigerator or ice box at all times and thus improve and simplify the present system in use by the ice companies using ice cards to indicate the wishes of the customer as to when a new supply of ice is needed. This invention therefore does away with all the troubles of the use of ice cards both for the consumers and the delivery man, as the indicator used in connection with the mechanism is automatic in operation and is constantly in full view of the ice man as he passes the house and indicates to him whether ice is needed or not.

A further object of the invention is to indicate the capacity of the refrigerator in the house to relieve the ice man from memorizing the customer's needs as it is always indicated by the indicator as he passes the house.

These and other objects of this invention will be fully illustrated in the drawing, described in the specification and pointed out in the claims at the end thereof.

In the accompanying drawing:

Figure 1 is a front elevation and partial sectional view of a refrigerator provided with the automatic indicating mechanism and its installation in the house.

Figure 2 is a partial top plan view and horizontal section of the refrigerator provided with the indicating mechanism.

Figure 3 is a detail perspective view of the indicator used in connection with the automatic indicating system.

Figure 4 is a detail perspective view of the part of the indicating mechanism that is mounted in the refrigerator.

Figure 5 is a horizontal sectional view of the follower arm and its guide tube, the section being taken on the line 5^x, 5^x of Figure 4.

In the several figures of the drawing, like reference numerals indicate like parts.

In the present day indicating system used by ice companies for the purpose of replenishing the consumer's supply of ice in the refrigerator, so-called ice cards are used. These cards are hung by the customer in a conspicuous place that is visible from the outside of the house to indicate to the ice man whenever he passes the house that ice is needed in the ice box. A constant supply of ice in the refrigerator thus depends on the customer being aware that a new supply is needed so that the ice card will be displayed

on the house to indicate to the ice man that more ice is needed. Many times the customer fails to display the card until after the ice man has passed the house and a special trip of the ice man is then necessary to replenish the supply of ice. Then too, the customer may be absent from the house for one or more days in which case all the food will spoil in the refrigerator because of lack of ice. The old method of using ice cards to indicate the supply of ice needed is thus inefficient for both the consumer as well as for the ice manufacturer or distributor. The indicating mechanism forming the subject matter of my present invention is adapted to make the indication automatic so as to relieve the customer from the responsibility of knowing just when and how much ice is needed in the refrigerator.

As illustrated in the several figures of the drawing, the automatic indicating system includes the mechanism which is mounted in the refrigerator and consists of a tubular guide 1. This guide is preferably mounted in the corner of the refrigerator and extends from the top of the ice compartment 2 to the bottom of the refrigerator. The upper end of the tubular guide 1 is fastened in place on the inside of the ice compartment by means of the bracket 3 which is fastened to the inside wall of the compartment and properly spaces the tubular guide therefrom. The lower end of the tubular guide is threaded and this end projects thru an opening in the bottom 4 of the refrigerator so that a nut 5 can be used to draw the collar 6 provided on the tubular guide down onto the bottom 4 with a suitable washer 7 between it and the bottom in order to seal the opening thru which the tubular guide projects.

Another collar 8 and washer 9 is provided intermediate of the ends of the tubular guide whenever the tubular guide has to pass thru an intermediate partition or bottom 10 in the refrigerator. This second collar and its washer is also drawn tight against the bottom and serves to seal the opening thru which the tubular guide projects.

The upper portion of the tubular guide 1 is provided with a vertical guide slot 11 which preferably extends the full length of the ice compartment of the refrigerator. A short horizontal slot 12 branches off from the vertical slot near the upper end thereof for a purpose that will presently appear. The follower arm 13 is adapted to slide up and down on

the tubular guide 1 and for this purpose is provided with the hub 14 at the inner end thru which the tubular guide can pass. On the inside the hub is provided with a small 5 radial projection or pin 15 which extends radially into the opening in the hub and is adapted to engage into the guide slot 11 when the follower arm is mounted on the tubular guide. In this way the following arm is held 10 to project from the tubular guide in a pre-determined direction which, as illustrated in the drawing, is preferably diagonal to the ice compartment so as to project over the block of ice 16 placed in the ice compartment 15 2 as illustrated in Figures 1 and 2. The follower arm 13, of course, has to be moved aside whenever a new supply of ice is inserted into the ice compartment. This is done by raising the follower arm until the pin 15 in the hub 20 of the arm can engage into the horizontal slot 12 allowing the arm to be swung aside parallel against the wall of the ice compartment as illustrated in dotted lines in Figure 2.

After the new supply of ice has been placed 25 into the compartment, the arm is swung back in place over the block of ice and allowed to constantly rest on top of it. As the ice melts and reduces the size, the follower arm follows the gradually diminishing block of ice until 30 the arm is halted from further movement by the adjustable collar fastened on the tubular guide at a predetermined point above the bottom of the ice compartment.

To automatically indicate the constantly 35 diminishing size of the ice supply in the refrigerator on the outside of the house by means of the follower arm 13 a wire or cable 18 is attached to the pin 15 of the follower arm by means of an expansion spring 19. 40 This wire and spring is located on the inside of the tubular guide 1 and extends thru the open end of the guide to the swinging arm 20 to which it is fastened. This arm is adapted to swing on the pivot pin 21 carried by the 45 bracket 22. The bracket and arm are mounted below the floor of the kitchen where the refrigerator is located and a small hole 23 in the floor allows the cable or wire 18 to pass from the tubular guide 1 to the end of the arm 50 20. In the arm 20 is fastened an adjustable clamp 24 to which another wire or cable 25 is fastened. This second cable extends to the indicator proper located on the outside of the house and passes below the floor over the pulleys 26 and 27 and then up within the outside wall to the pulley 28 and over the roller 29 to the indicator weight 30 to which it is attached. The pulleys 26 and 27 are suitably 55 supported on the joist or other parts of the frame of the house while the pulley 28 and roller 29 are carried on the casing 31 of the indicator proper. The pulley 28 is carried by an arm which projects rearwardly from the casing 31 and when mounting the casing to the outside of the wall, a hole is drilled into 60

the wall to allow the arm with its pulley to project into the wall.

The indicator casing 31 is suitably mounted to the wall, and within it is mounted the indicator weight 30. This weight has suitably 70 fastened thereto the indicator plate 32 which is provided with a narrow arm that projects to one side thru the slot to the top of the indicator weight to which it is suitably fastened. 75

As the indicator weight within the casing falls, the indicator plate on the outside of the casing falls with it and by its position indicates the amount of ice needed to replenish the supply in the refrigerator as will presently 80 appear. On the front face of the indicator casing 31 are the marks 00, Half and 100. Of these the marking 00 is at the top of the indicator casing so that when the lower edge of the indicator plate 32 is in line with this 85 marking it shows that no ice is needed in the refrigerator as the ice compartment of it is full. A drop of the indicator plate to the half mark indicates that half of the ice is melted and should be replenished according 90 while a drop to the 100 mark indicates that the ice supply in the refrigerator is practically gone and needs an entirely new supply. The 100 mark indicates 100 pounds and is used whenever the capacity of the ice compartment of the refrigerator in which this 95 indicating system is used is 100 pounds. For smaller refrigerators the 100 mark would be replaced by the capacity in the number of pounds that the refrigerator is rated. Thus 100 a refrigerator having an ice capacity of but 50 pounds would have a marking of 50 at the bottom of the indicator casing showing that a new supply of 50 pounds of ice is needed to replace the original supply that has melted 105 away.

The adjustable collar 17 of course, does not allow the follower arm to drop below a certain point on the tubular guide 1 and the position of this collar, and the movement of the indicator plate with relation to the movement of the follower arm is so adjusted that at the point where the follower arm is halted by the collar 17 a small supply of ice is still left within the ice compartment in spite of the fact 110 that the indicator shows that an entirely new supply of ice is needed in the refrigerator. This is to avoid having all of the ice melted before a new supply is placed in the refrigerator. The weight in the indicator casing 115 thru the cables 25 and 18 and the spring 19 keeps the follower arm constantly on top of the gradually melting ice supply and as the ice melts the weight drops in the indicator casing giving the resulting indication above 120 described. 125

The spring 19 is adapted to allow the follower arm to be raised even after the indicator weight has reached its uppermost position. The position of the follower arm in 130

its full line position indicated in Figure 1 is, therefore, indicated by the 00 mark on the indicator casing, and the raising of the follower arm into the dotted line position to 5 allow a new supply of ice to be placed into the ice compartment will not change this indication of the indicator.

In the winter time or at any time when no 10 ice is wanted, the follower arm may be kept in the elevated dotted line position to indicate that no ice is wanted.

The adjustable clamp 24 on the arm 20 is placed in the proper position in which the range of movement of the follower arm will 15 be translated by it into the range of movement of the indicator weight and its indicator plate. The indicator plate may be made large enough to have the name of the ice company delivering the ice located on it so that the 20 use of this indicating system serves as an advertisement for the ice company using it.

It will be seen from an inspection of the drawing that the construction and operation of the follower arm and its mounting is such 25 that it can be readily installed in all types of refrigerators whether the ice door is located on the side, top or end of the refrigerator.

I claim:

1. In an ice supply indicating system for 30 refrigerators, the combination of a stationary guide member located within the refrigerator, a follower arm mounted to slide down on said guide member and adapted to rest on top of the ice supply in the refrigerator, an indicator, and means for transmitting the motion 35 of said follower arm to said indicator.

2. In an ice supply indicating system for 40 refrigerators, the combination of a tubular guide member having a vertical guide slot with a horizontal extension in the slot near 45 the top thereof, a follower arm adapted to slide up and down on said tubular guide member, a guide pin carried by said follower arm and adapted to engage into said guide slot to hold said follower arm fixed in a predetermined position during its travel on said tubular guide member, and allow said follower arm to swing to one side of the fixed posi-

tion on the engagement of said pin into the horizontal extension of said guide slot, a 50 spring attached to the follower arm within said tubular guide member, a cable attached to said spring, a swinging arm pivoted below said refrigerator, said cable being attached to the end of said arm, an adjustable clamp 55 carried intermediate of said arm, a second cable attached to said adjustable arm at one end thereof, an indicator weight attached to said second cable at its other end thereof, an indicator housing surrounding said indicator weight the movement of said indicator weight within said indicator housing being controlled by the movement of said follower arm thru said first and second cable. 60

3. In an ice supply indicating system for 65 refrigerators, the combination of a tubular guide member having a vertical guide slot with a horizontal extension in the slot near 70 the top thereof, a follower arm adapted to slide up and down on said tubular guide member, a guide pin carried by said follower arm and adapted to engage into said guide slot to hold said follower arm fixed in a predetermined position during its travel on said tubular guide member, and allow said follower 75 arm to swing to one side of the fixed position on the engagement of said pin into the horizontal extension of said guide slot, a spring attached to the follower arm within said tubular guide member, a cable attached to said 80 spring, a swinging arm pivoted below said refrigerator, said cable being attached to the end of said arm, an adjustable clamp carried intermediate of said arm, a second cable attached to said adjustable arm with one end 85 thereof, an indicator weight attached to said second cable at its other end thereof, an indicator housing surrounding said indicator weight the movement of said indicator weight within said indicator housing being controlled by the movement of said follower arm thru said first and second cable, and means 90 for limiting the movement of said follower arm in one direction.

In testimony whereof I affix my signature.
FRANK J. SCHROEDER.
